CLAIM

The ornamental design for a catheter package with twist cap, as shown and described.

DESCRIPTION

FIG. 1 is a perspective view of a catheter package with twist cap;

FIG. 2 is a front elevation view thereof, with the left, right and rear elevation views being the same as shown;

FIG. 3 is a top plan view thereof; and,

FIG. 4 is a bottom view thereof.

The broken lines depict portions of the article that form no part of the claimed design.
